ATTORNEY

UNITED STATES PATENT OFFICE.

JACOB P. RICHE, OF KANSAS CITY, MISSOURI.

SUPPORT FOR METAL TRAYS.

Application filed February 16, 1925. Serial No. 9,559.

This invention relates to supports for metal trays and while the generic principle involved contemplates various uses of the invention it is particularly designed in connection with a tray runway for cafeterias.

The tray supports or runways prior to my invention were provided with rails which accumulated a black sooty substance due, in a large part, to the fact that the metal from the bottom of the trays rubbed off upon the surfaces of the rails so that as the customers passed along in front of the serving stations their hands, gloves or garments came into contact with the rails with the result that they were soiled.

This objectionable annoyance has heretofore been characteristic of all cafeterias and managers have incurred considerable expense and loss of time experimenting to provide or find some suitable material from which to make the runways so that the metal from the trays would not soil the rails and in turn cause the rails to soil the hands and garments of the patrons.

I have found that the objections above enumerated can be entirely eliminated by providing a material to which the metal molecules or particles will not adhere as the trays are passed along over the rails. Considerable difficulty has been experienced and much experimentation has been resorted to to find a material which will not have an affinity for metal. I have found, however, that a material commonly known as bakelite admirably serves the purpose desired to be accomplished by this invention. When the rails of the runway are made of bakelite or material having the characteristics of bakelite, in so far as the attraction for metal is concerned, trays may be moved over the rails at will without depositing the soot-like coating upon the surfaces thereof, the result being that the rails will remain clean and free of accumulations from the bottom of the trays, consequently the hands, gloves and garments of the patrons do not become soiled, to the great relief of the cafeteria operatives who under the old practice found

it necessary to continually explain the reason for the apparent dirt on the runways.

The invention will be more clearly understood by reference to the following description in connection with the accompanying drawings, in which

Fig. 1 is a fragmentary, perspective view of a runway and several service stations, the runway being constructed in accordance with my invention, and

Fig. 2 is a fragmentary end perspective view of the runway.

The service stations 1, 2 and 3 merely represent some of a long row or bank of service station such as may be found in any modern cafeteria. The service station structure supports a plurality of angular brackets 4 each having a horizontal, laterally disposed arm 5 preferably braced by a diagonal brace 6. These arms 5 support the parallel members 7 and 8 of the runway. These may be made of wood or any inexpensive material and they are grooved as indicated at 9 and 10 to receive the bakelite strips or rails 11 and 12 which may be removably secured in the grooves by the set screws 13 and 14. Extending through the bottoms of the respective members 7 and 8 are vertical screws 15 and 16 which may be adjusted to level the rails 11 and 12 or to assist in forcing them from the grooves when it is necessary to replace the rails for any purpose. The upper surfaces of the rails 11 and 12 are preferably fluted or corrugated as at 17 and 18. This is for the purpose of reducing the engaging surface between the trays and the rails. The tray is shown in dotted lines in Fig. 1 and is designated 19.

The importance of this invention can be appreciated with the knowledge that hundreds of trays can be passed over the bakelite rails without leaving a deposit of metal such as would soil the hands or garments of the patrons should either of these, or both, come into contact with the rails, whereas with the present runways the rails become soiled after a comparatively small number of trays have passed over them.

In place of bakelite I may substitute a material known as hard fibre, but I recommend bakelite because of its wearing quality, its appearance and because of the actual results obtained.

What I claim and desire to secure by Letters-Patent is:—

A runway for metal trays comprising a supporting rail substantially rectangular in

cross section having an upper corrugated portion adapted for slidable contact with the bottom of a tray, and the lower portion of said rail adapted for seating within the slot of a base rail member, and means in the bottom of said base rail for adjusting the contained rail relative thereto.

In testimony whereof I affix my signature.

JACOB P. RICHE.
